UNITED STATES PATENT OFFICE.

JAMES A. BROOKS, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

CAR-SEAT.

1,371,848.

Specification of Letters Patent. Patented Mar. 15, 1921.

Application filed September 1, 1920. Serial No. 407,513.

To all whom it may concern:

Be it known that I, JAMES A. BROOKS, a citizen of the United States, residing in Philadelphia, Pennsylvania, have invented 5 certain Improvements in Car-Seats, of which the following is a specification.

My invention relates to certain improvements in car seats, particularly those used for city and suburban service.

10 One object of the invention is to provide a car seat in which the seat section can be raised and moved against the back of the seat so as to more readily allow ingress and egress to the space between the seats. A 15 further object of the invention is to so connect the seat section to the frame as to insure the proper positioning of the seat section when shifted from one position to another.

In the accompanying drawings:

20 Figure 1 is an end view of a car seat illustrating my invention;

Fig. 2 is a side view;

Fig. 3 is an enlarged sectional view on the line 3—3, Fig. 2; showing the seat section in 25 its normal position;

Fig. 4 is a similar view showing the seat section raised;

Fig. 5 is a perspective view of the shifting bar and its arms; and

30 Fig. 6 is a detached perspective view of the stop which limits the movement of the seat.

In the present instance, the invention is 35 illustrated as a wall seat, *i. e.*, one in which there is but a single pedestal at the aisle end of the seat for supporting the seat structure, the inner end of the seat structure being supported on a bracket 2 secured to the frame of the car, as shown clearly in Fig. 2.

40 The pedestal 1, the seat support 4 and the back support 5 are made in the form of an integral structure, in the present instance. The back 6 is rigidly secured to this structure at the aisle end and to a back sup-

45 port 7 at the wall end. The wall end of the seat section 8 rests on a flange 9 of the bracket 2 secured to the side 3 of the car and at the aisle end this seat section is supported by the end portion 4 of the pedestal 50 structure.

In order to locate the seats as close together as possible, I have found that it is desirable to design the seat structure so that the seat sections can be raised and tilted

back against the back section to allow passengers to pass readily through the space between one seat and a seat in front of it. The structure for accomplishing this should be such that it can be easily raised and lowered by a passenger.

55 10 is a longitudinal rod secured to the bracket 2^a at one end by a nut 3^a, and at the other end extending into a socket in a bushing 11 located in the side member 4. On this rod is a tube 16 to which are secured two 60 arms 12 and 13, which are pivotally connected to brackets 14 and 15 respectively, secured to the under side of a car seat near the rear thereof.

65 This construction is very simple and when it is desired to raise a seat from the position shown in Fig. 3, to that shown in Fig. 4, all that is necessary is to raise the front edge of the seat and the arms will hold the seat in position while being elevated.

70 75 In order to prevent the lower edge of the seat moving forward when the seat is elevated, as in Fig. 1, a stop 17 is provided, which may be attached to the wall bracket 2 or to the pedestal 1, as desired. This stop 80 has a projection 18 against which rests one of the arms 12 or 13.

75 It will be noticed that the arms connecting the seat section are limited in their forward movement by the stops, and when the seat 85 section is lowered they are at such an angle as to insure the seat section assuming a proper position on its support, as gravity due to the weight of the rear of the seat will overcome any friction due to the rubbing of 90 the seat section against the frame at its forward end. Furthermore the rock shaft is so located that the seat section will rest firmly on the frame when lowered.

95 The arms are so pivoted to the seat section that the inner edge of the section will not rub against the frame in moving from one position to another, and when the seat section is raised it will be supported entirely by the rock shaft and its arms, and when 100 lowered will be supported entirely by the frames.

I claim:

1. The combination in a car seat, of two 105 end frames; a back section connected to the frames; a seat section mounted on the end frames; and arms pivoted to the end frames in front of the seat section, when said seat

section is raised, and connected to the under side of the seat section, said arms supporting the seat section clear of the frame when raised and preventing the forward movement of the seat section when said seat section is resting on the frames.

2. The combination in a car seat, of two end frames; a back section connected to the end frames; a rod extending from one end frame to the other; a tube loosely mounted on the rod; arms at each end of the tube; and a seat section mounted on the frames, the rods being connected to the under side of the seat section near the rear, the rod being in such position in respect to the seat section that the arms will support the seat section when raised against the back and

will hold the seat section against outward movement when said seat section is resting on the frames. 20

3. The combination in a car seat, of two frames spaced apart, one frame being supported by a pedestal; a back section securing the two arms; a seat section mounted on the arms; a rod secured to one frame and extending into a bushing in the other frame; a tube mounted on the rod; two arms secured to the tube; brackets on the under side of the seat section to which the arms are pivotally connected, said brackets being 25 located near the rear of the seat section; and a stop to limit the forward movement of the seat section when the seat section is raised.

JAMES A. BROOKS.
